CHAIN LINK WIRE FABRIC

Arthur A. G. Land, Chicago, Ill.

Application March 26, 1931. Serial No. 525,459

12 Claims. (Cl. 245—6)

My invention relates to chain-link wire fabrics, namely fabrics formed of flattened spiral strands (or so-called zig-zag wires) which extend transversely of the fabrics with each strand presenting bights at each edge of the zigzag strand and in which consecutive strands are intertwined to form mesh with interlocked bights so that the interlocked bights of consecutive strands afford hinging connections which permit the fabric to be rolled up.

Chain-link wire fabrics have long been popular for many classes of fence and grilles both because they are easily and cheaply manufactured, because they can readily be rolled up for storage and shipment even when made of heavy and stiff wire, because they can easily be spliced to one another without employing auxiliary wire and without having the joints show, and because any desired length of the fabric can easily and quickly be severed from a roll of such fabric.

However, the chain-link wire fabrics as heretofore in use, which have meshes of a so-called diamond-shape with the sides of the mesh at acute angles to the axis of the strands, cannot be longitudinally tensioned to any considerable degree—as when stretching such fabrics between widely spaced fence posts—without distorting the shape of the meshes and contracting the fabric in width. Consequently, such fabrics have only been extensively used when it was permissible also to provide stiff rails or auxiliary wires extending longitudinally of the fabric at both edges of the fabric, to which the fabric can be attached so as to be entirely framed by auxiliary stiffening members.

My present invention aims to provide a chain-link wire fabric composed of strands having zigzag formations so formed as to afford interlocked portions extending longitudinally of the fabric, which portions cooperate to take the longitudinal tensioning strains, thereby permitting the fabric to be adequately tensioned even when made of relatively light wire.

Furthermore, my invention aims to provide easily manufactured and readily intertwined constituent strands for chain-link wire fabrics in which mesh sides form novel but simple strand portions which impart an enhanced longitudinal strength to the fabrics which may also have other forms of meshes and aims to provide strand constructions which will readily permit the number and location of these strand portions to be varied within a wide range and according to the size and shape of meshes and

according to the degree of tensioning strength and resiliency required in the fabric.

Furthermore, my invention aims to provide rigidity enhancing strand and fabric constructions for chain-link wire fabrics, which strands can readily be formed to afford wide variations both in the relative length and width, and in the contour of the resulting meshes so as to produce ornamental fabrics of widely varying appearance; and which will also permit such fabrics to withstand much more severe longitudinal tensioning than has been permissible with chain-link fabrics of the diamond-mesh type heretofore employed.

Also, my invention aims to provide upright chain-link wire fabrics also composed of consecutively intertwined strands, but including meshes which present at least six bights interlocked with adjacent meshes; thereby permitting wire of a given diameter and rigidity to be used effectively in fabrics presenting meshes of relatively great height in proportion to the width of the meshes.

Also, my invention aims to provide constituent strands for upright chain-link wire fabrics which when consecutively intertwined will afford meshes each having more than two pairs of interlocking bights and other meshes having only two interlocking bights and which may include meshes having four interlocking bights.

Still further and also more detailed objects will appear from the following specification and from the accompanying drawings, in which drawings

Fig. 1 is an elevation of a portion of a wire fabric embodying my invention in which the major mesh in each series have their bases in alinement and extending longitudinally of the fabric and in which the strand portions extending from the apices of these mesh are in alinement and also extend longitudinally of the fabric.

Fig. 2 is an elevation of one of the constituent strands of the fabric of Fig. 1.

Fig. 3 is a side elevation of the strand shown in Fig. 2, taken from the right-hand side of the strand.

Fig. 4 is a side elevation of an alternative strand formation for strands producing the meshes of Fig. 1.

Fig. 5 is a plan view of the strand of Fig. 2.

Fig. 6 is an elevation of a portion of a chain-link wire fabric of the ordinary diamond-mesh type with the strands formed to afford the same height and spread as the major meshes in Fig. 1, with dotted lines showing the distortion of the

85

100

110

- mesh by longitudinal tensioning in the direction of P.
- Fig. 7 is an elevation of a portion of the fabric of Fig. 6 in which the mesh is distorted to a greater degree, showing the larger size object D² that will pass through this mesh as compared with the size of the object C that will pass through the same mesh before it has been distorted by a longitudinal tensioning.
- 10 Fig. 8 is an elevation of a portion of a wire fabric embodying my invention in which the major mesh in each series each has two apices and in which the strand portions extend from these apices longitudinally of the fabric.
- 15 Fig. 9 is an elevation of a portion of a wire fabric embodying my invention in which the strands are formed to present major meshes having eight bights.
- Fig. 10 is an elevation of a portion of a wire fabric embodying my invention in which the bight spacings in the upper mesh series are equal and the bight spacings in the lower mesh series are unequal, thereby forming different shaped major and secondary mesh.
- 20 25 Fig. 11 is a diagrammatic elevation of a portion of a wire fabric embodying my invention with the mesh series also including deltoid-shaped mesh.
- Fig. 12 is an elevation of a portion of a wire fabric embodying my invention which includes strands having side edge bights alternately on each side.
- 30 35 Fig. 13 is an elevation of a portion of a wire fabric embodying my invention in which the major mesh in each series each has two bases which extend longitudinally of the fabric.
- Fig. 14 is a diagrammatic elevation of a portion of my fabric in which the upper mesh series includes two longitudinal rows of major mesh and the lower mesh series includes one longitudinal row of major mesh and both mesh series include additional deltoid-shaped mesh.
- 40 45 Fig. 15 is a diagrammatic elevation of a portion of my fabric in which each mesh series has more than one row of major mesh and in which the major mesh are of different heights and shapes.
- Fig. 16 is a diagrammatic elevation of a portion of my fabric which includes diamond-shaped mesh in one mesh series.
- 50 Fig. 17 is a diagrammatic elevation of a portion of my fabric in which each mesh series has different height and different shaped major mesh.
- Fig. 18 is a diagrammatic elevation of a portion of my fabric in which each mesh series includes deltoid-shaped mesh.
- 55 60 Fig. 19 is a diagrammatic elevation of a portion of my fabric in which one mesh series has two different height and shaped major mesh and also diamond-shaped mesh.
- Fig. 20 is a diagrammatic elevation of a portion of my fabric in which one mesh series has two longitudinal rows of major mesh which are the same height and shape and which also includes a row of diamond-shaped mesh.
- 65 Fig. 21 is a diagrammatic elevation of a portion of my fabric in which each mesh series has only one longitudinal row of mesh legs and which also includes diamond-shaped mesh.
- 70 75 In accomplishing the purposes of my invention I employ spiral strands transversely of the fabric intertwined through each other to form rows of mesh longitudinally of the fabric, with the mesh of certain longitudinal rows having strand portions or mesh sides which extend longitudinally
- of the fabric and which will take the longitudinal tensioning strains. With the ordinary diamond-shaped mesh, when the fabric is tensioned longitudinally and the mesh elongated longitudinally the mesh also contract transversely of the fabric.
- Fig. 6 shows a mesh of ordinary diamond-shape of the same spread and height as the mesh of Fig. 1 with the dotted lines showing the distortion of this mesh when tensioned longitudinally or in the direction of P. If this mesh is tensioned so that the angles between the legs are square angled the effective mesh opening becomes larger as shown by comparing the size object C of mesh in Fig. 6 with the size of object D² in mesh of Fig. 7, which mesh has the same length mesh sides or legs as mesh of Fig. 6. I overcome this objection by employing mesh shapes which include mesh having strand portions or mesh sides which extend longitudinally of the fabric and which will withstand the longitudinal tensioning strains and which will materially reduce the extent to which the mesh in my fabric can be distorted.
- Illustrative of such a simple type of my wire fabric as shown in Fig. 1, which is composed of flattened spiral strands formed as shown in front elevation in Fig. 2 and in side elevation in Fig. 3 and Fig. 4, each two consecutive strands are relatively laterally reversed in the assembled fabric. In each of these strands of Fig. 2 the formation of the strand section V is continuously repeated. This formation includes a bight 4 at the right-hand edge of the strand, a strand leg 5 leading from the bight 4 to a bight 6 at the left-hand edge of the strand and a strand leg 7 extending from bight 6 to bight 8 at the right-hand edge of the strand and a V-shaped mesh side formed by portions 9 and 11 which has its major portion between the line L (along which all of the bights at the left-hand edge of the strand aline) and the line Y along which all of the bights at the right hand edge of the strand aline and with the bight 10 connecting the strand portions 9 and 11.
- Also the consecutive bights 4 and 8 at the right-hand edge of the strand of Fig. 2 are between two consecutive bights 6 at the left-hand edge of the strand, and the strand portions (or legs) 9 and 11 extend from the bights 4 and 8 part way toward the left-hand edge of the strand.
- As shown in side elevation, Fig. 3, the alternate strand legs 7 and 11 are in the same plane A, and the legs 5 and 9 are in the same plane B. As the bight 10 does not interlock with an adjacent strand in the assembled fabric this bight may be eliminated as shown in side elevation Fig. 4, and the strand portions 10 and 11 may have their major portions between the planes A and B and extending from plane A to plane B. The legs 5 which extend from bights 4 to bights 6 cross the axis K of the strand at right angles as shown in Fig. 2.
- When such strands are consecutively intertwined as in Fig. 1 the strand portions 7, 9, 11 and 5 between bights 6 form one-half of the outline of a six-bight major mesh M which has these bights respectively at its upper corner or apex, at the sides and three bights at its lower side or base, and the strand portions 9 and 11 between bights 8 and 4 also form one-half of the outline of a secondary mesh S having only two bight corners, namely the upper and lower corners. The apices or upper parts of the major mesh M have bights 6 which connect the strand portions or legs 5 which are in alinement and

these portions also form the base of the major mesh M in an adjacent mesh series. The legs 5 are connected by bights 6 to legs 7 which together with the strand legs 5 form the four-bight mesh I which is triangular shaped. The bight spacings C as shown in Fig. 2 are equal and the bight spacings D are equal. However, the spacings C and D are unequal, but these spacings may vary or may be equal. So also the space T between line Y at the right-hand edge of the strand and bight 10 may vary.

The strands are continuously spiraled in the same direction as shown in Fig. 5, which is a plan view of the strand, and when these strands are assembled by intertwining one through the other and interlocking the side edge bights of each strand with the side edge bights of the adjacent strand they form series or sections of mesh rows longitudinally of the fabric with each series in Fig. 1 consisting of one row of major six-bight mesh M, one row of secondary two-bight mesh S and one row of four-bight mesh I. The apex or end of each major mesh in each series has interlocked bights 6 from which strand portions or legs 5 extend in opposite directions and in alignment longitudinally of the fabric. Also the other end or the base of each major mesh M in the same series has strand portions or legs 5 extending from interlocked bights 6 in alignment with each other and longitudinally of the fabric so that each mesh series is bordered by a longitudinal row of mesh legs 5 which, in the assembled fabric, form continuous strand portions which are in alignment longitudinally of the fabric and which take the longitudinal tensioning strains.

The longitudinal rows of strand portions 5 which are spaced from both longitudinal edges of the fabric are common to two mesh series or mesh sections. For example, in Fig. 1 the second longitudinal row of strand portions 5, counting from the top, is common to both the top mesh series and the mesh series next to the top.

Figs. 15 and 18 show a fabric in which only one end of the major mesh M has interlocked bights from which the strand portions extend in alignment with each other and longitudinally of the fabric, so that the fabric will have the greater number of the strand portions extending at acute angles to the longitudinal edges of the fabric, with each mesh series including several varieties of mesh shapes.

The bights 4, 6 and 8 of each strand of Fig. 1 are so formed that when the assembled fabric is tensioned the major portions of all the strands will be approximately in two parallel planes as shown by the lines A and B in Fig. 3, or may have portions of the strands (as for example strand portions 9 and 11 in Fig. 4) which extend between the two planes in which the major portions of the strands of the fabric are located.

While I have described the strand legs or mesh sides as being straight, I do not want to be limited as to the shape of these legs or mesh sides, as these may vary as shown in the right-hand row of major mesh M in Fig. 1, which shows the mesh sides (between the interlocked bights) with bent portions, which in addition to producing an ornamental effect also reduce the effective mesh opening as shown by comparing the size of the round object E in the right-hand row of mesh with the round object G as shown in the left-hand row of mesh.

While I have described the mesh of my fabric as having unequal bight spacings as shown by the bight spacings C and D of Fig. 1, I do not want

to be limited as to the spacings of these bights, as they may vary, as for example the bight spacings D, C¹ and C² in upper series of mesh of Fig. 10 are equal, while in the lower mesh series the bight spacings D¹, H and H¹ are unequal, so that the secondary mesh S in the assembled fabric have unequal length sides, and both the major mesh M and secondary mesh S in each series have different shapes.

Furthermore, I do not want to be limited as to the shape of the major mesh, as these major mesh may be formed to have two apices, as for example, Fig. 10 shows a fabric in which each major mesh has two apices so that the mesh have at both the upper and lower apices strand portions 5 extending in opposite directions and in alignment longitudinally of the fabric, thereby forming in each mesh series a longitudinal row of six-bight major mesh M, a longitudinal row of two-bight secondary mesh S and two rows of four-bight auxiliary mesh I. Also, the shape of both the major and secondary mesh may vary by changing the form of the mesh sides, as shown by the upper longitudinal row of major mesh M and secondary mesh S of Fig. 8. So also the major mesh M may have both top and bottom mesh sides 5 in alignment longitudinally of the fabric as shown in Fig. 13, so that the three bights at each end of each mesh are approximately in alignment longitudinally of the fabric, forming mesh series in which the secondary mesh S are approximately the same height as the major mesh and which include a longitudinal row of four-bight auxiliary mesh which are alternately upright and inverted.

Moreover, the major mesh in my fabric may have more than six bights, as Fig. 9 shows a portion of my fabric similar to the fabric of Fig. 1 in which the major mesh M' have eight interlocked bights forming in each mesh series two longitudinal rows of two-bight secondary mesh S and only one row of eight-bight major mesh M' and one row of four-bight auxiliary mesh I.

Also, I do not want to be limited in the use of these strands, as they may be used in connection with strands having the bights on each side edge alternating, as for example, Fig. 12 shows a portion of a fabric in which strands W, which have side edge bights alternating, are interwoven with my new strands Z, which have pluralities of consecutive side edge bights.

Moreover, I do not want to be limited in the quantity of the major mesh used in a mesh series or to the shape of these mesh or to the shape or quantity of the secondary or the auxiliary mesh or to the use of additional mesh in the fabric, as many changes may be made without departing from the spirit of my invention, as for example, Figs. 11, 14, 15 and 18 shows portions of my fabrics in which deltoid-shaped mesh X are included in the mesh series; while Figs. 16, 19, 20 and 21 show fabrics in which the mesh series include diamond-shaped mesh R; Fig. 17 shows a portion of my fabric in which three different shaped major mesh M are used; and Fig. 19 shows a portion of my fabric in which the upper mesh series includes a longitudinal row of diamond-shaped mesh R while in the lower mesh series these mesh are not included. Also, Fig. 21 shows a fabric in which each mesh series has only one longitudinal row of mesh legs 5 which take the longitudinal tensioning strains and the fabric also includes longitudinal rows of four-bight mesh R.

It will also be obvious from the drawings that I can provide the severely tensionable strand

portions in fabrics having widely different shapes of meshes, as shown for example by a comparison of Figs. 8, 12, 14 and 16; also, that with meshes of given general shapes, the relative heights and widths of the meshes may be varied. So also, the number of longitudinal lines along which the tensioning is effected and the relative spacing between these lines may be varied—as shown for example by comparing Figs. 10, 11, 13, 17 and 18. Moreover, the manner in which the free ends of the adjacent strands are secured to each other at the longitudinal edges of the fabric is immaterial as far as my present invention is concerned, since this invention in its major aspects aims to provide means which will permit a longitudinal tensioning of the fabric also along one or more lines spaced from the lateral edges of the fabric, while still having the advantages of using mesh shapes which present at least six interlocked bights, and which fabric may also include mesh shapes having only four interlocked bights.

I am aware that some heretofore proposed wire fabrics have been formed so as to present highly tension-resisting longitudinal edges while having the entire remaining portion of the fabric highly resilient and incapable of any considerable tensioning. I am also aware that wire fabrics have heretofore been manufactured by consecutively intertwining zigzag wire strands; but these strands invariably have all of the zigzag formations in each strand counterparts of each other, and have the consecutive spacings between bights at the same edge of any single strand equal, it having been commonly assumed that zigzag strands could only be intertwined when they have the just recited characteristics which cause each two intertwined strands to border meshes of uniform resistance to tensioning.

However, I have discovered that zigzag strands can also be consecutively intertwined into a fabric when the zigzag formations in each strand are not all counterparts of one another, when the consecutive spacings of the bights at one edge of a single strand are not all equal, and when the alternate legs of the strand are not all parallel to one another. By employing this discovery, I am able to use consecutively intertwined strands as the entire constituents of wire fabrics in which the resistance to a tensioning of the fabric (in a direction at right angles to the axes of the strands) can be greatly varied in different fabric portions spaced transversely of the fabric, whereby the fabrics will present either longitudinal "tensioning lines" (each composed of single legs of consecutive strands) or longitudinal rows of highly tension-resisting meshes; whereby the remaining meshes can be formed so that strains on them will be partly transmitted to these tensioning lines or rows of higher-tension-resisting meshes; and whereby the appearance of such wire fabrics can be greatly varied and improved.

While I have shown several forms of this fabric and mesh arrangement, I do not want to be limited as to the arrangements or number of mesh rows or series of mesh rows, nor to the details of construction, or shapes of the mesh sides, or to the shape of the side edge bights of the strands since many changes may be made without departing from the spirit of my invention or from the appended claims.

Furthermore, it is to be understood that the term "mesh side" or "leg" in the appended claims is used to designate the entire portion of a single strand which is interposed between any two con-

secutive bights of a strand; and that the term "bight" is used to designate the bends of adjacent strands which are interlocked in the assembled fabric.

I claim as my invention:

1. A chain-link type of wire fabric comprising consecutively intertwined spiral strands of zigzag formation in elevation, each presenting a row of alined bights at each longitudinal edge of the zigzag strand, the said formation being such that two consecutive strands border meshes presenting at least six interlocked bights, with the strand portions which extend from the interlocked bights at one end of each such mesh in alinement with each other longitudinally of the fabric.

2. A chain-link type of wire fabric comprising consecutively intertwined spiral strands of zigzag formation in elevation, each strand presenting a row of alined bights at each longitudinal edge of the zigzag strand, the said formation being such that two consecutive strands border meshes presenting not less than six interlocked bights, each such mesh having at one end interlocked bights from which strand portions extend in alinement with each other longitudinally of the fabric.

3. A chain-link type of wire fabric comprising consecutively intertwined strands having a zigzag formation in elevation, each strand presenting a row of alined bights at each edge of the strand, which bights in adjacent strands are interlocked; the zigzag formation being such that intertwined strands form meshes, including major meshes, each having a plurality of pairs of laterally disposed mesh side bights interposed between mesh end bights, and secondary meshes, each of which has two end bights but no side bights, the said major meshes each having at one end of the mesh interlocked bights from which strand portions extend in alinement longitudinally of the fabric.

4. A chain-link type of wire fabric comprising consecutively intertwined spiral strands of zigzag formation in elevation, the said formation being such that the strands border meshes arranged in sections longitudinally of the fabric with strand portions which are common to consecutive sections extending in alinement with each other longitudinally of the fabric, the said mesh sections including meshes having six interlocked bights.

5. A chain-link type of wire fabric comprising consecutively intertwined spiral strands of zigzag formation in elevation, each strand presenting a row of alined bights at each longitudinal edge of the zigzag strand, the said formation being such that the strands border meshes extending longitudinally of the fabric which include meshes having at least six interlocked bights, each such six-bight mesh having at one end interlocked bights from which strand portions extend in alinement with each other and longitudinally of the fabric.

6. A chain-link type of wire fabric comprising consecutively intertwined strands having a zigzag formation in elevation and presenting a row of alined bights at each edge of the strand, which bights in adjacent strands are interlocked; the zigzag formation being such that the intertwined strands form meshes arranged in sections longitudinally of the fabric which include meshes having at least six interlocked bights, the fabric also including strand portions which extend longitudinally of the fabric and are in alinement with each other.

7. A strand for a chain-link wire fabric, com-

- prising a wire formed into a zigzag flattened spiral presenting bights at each longitudinal edge of the strand, with strand portions connecting these bights, some of which portions cross the longitudinal axis of the strand at right angles; the strand being formed to dispose pluralities of consecutive bights at one edge of the strand between two consecutive bights at the other edge of the strand. 5 80
- 10 8. A strand for a chain-link type of wire fabric, comprising a flattened spiral strand of zigzag formation presenting pluralities of groups of bights, the bights of each group being consecutive at the same edge of the strand and alining longitudinally of the strand with each other and with bights of the other groups at the same edge of the strand, each such group of bights being disposed between two consecutive bights which are disposed at the other edge of the strand, the strand portions connecting the consecutive bights of each group being offset from the strand edge along which these bights aline and toward the opposite edge of the strand; the strand also including strand portions which cross the longitudinal axis of the strand at right angles. 15 90
- 20 9. A strand for a chain-link type of wire fabric, comprising a wire formed into a flattened spiral of zigzag formation presenting bights at each longitudinal edge of the strand, with each two bights connected by a strand portion, one of which portions crosses the axis of the strand at right angles; the strand being formed to dispose pluralities of consecutive bights in the strand at one edge of the strand between two consecutive bights at the other edge of the strand, the strand portion between the first-named two consecutive bights extending part way towards the opposite edge of the strand. 25 105
- 30 10. A strand for a chain-link wire fabric, comprising a wire formed into a flattened spiral presenting bights alining respectively at each longitudinal edge of the strand, with strand portions 35 110

- connecting each two bights, the strand being formed so as to dispose pluralities of consecutive bights in the strand at one edge of the strand between consecutive bights at the other edge of the strand, the strand including a portion connecting two consecutive bights and which crosses the axis of the strand at rights angles. 85
11. A chain link type of wire fabric comprising consecutively intertwined flattened spiral strands of zigzag formation in elevation, each presenting a row of alined bights at each longitudinal edge of the zigzag strand and strand legs connecting these bights, each strand including a portion in which two bights at one edge of the strand are disposed between two consecutive bights at the opposite edge of the strand and each such portion including at least one strand leg extending in a direction at right angles to the general axis of the strand, whereby these portions of two adjacent strands form a mesh presenting at least six interlocked bights, with the strand legs which extend from the interlocked bights at one end of the mesh extending longitudinally of the fabric. 90
12. A chain link type of wire fabric comprising consecutively intertwined strands having a zigzag formation in elevation, each strand presenting a row of alined bights at each edge of the strand, which bights in adjacent strands are interlocked; each strand including a portion in which pluralities of consecutive bights at one edge of the strand are disposed between two consecutive bights at the other edge of the strand and each such portion also including a strand leg extending in a direction at right angles to the general axis of the strand so that such strand portions in adjacent strands form meshes having at least six interlocked bights, with the strand legs which extend from the interlocked bights at one end of each such mesh extending in a direction at right angles to the general axes of the strands. 115 110

ARTHUR A. G. LAND.
